SWITCH OPERATING MECHANISM

Filed Oct. 1, 1929

Inventor:
George Pailin,
by Charles O. Tulla
His Attorney.

UNITED STATES PATENT OFFICE

GEORGE PAILIN, OF MANCHESTER, ENGLAND, ASSIGNOR TO GENERAL ELECTRIC COMPANY, A CORPORATION OF NEW YORK

SWITCH OPERATING MECHANISM

Application filed October 1, 1929, Serial No. 396,567, and in Great Britain October 11, 1928.

My invention relates to circuit breakers, member coupled in a suitable manner to the and more particularly to switch operating switch arm or its equivalent (not shown). mechanism of the type permitting trip-free action of the switch in response to an abnormal circuit condition.

A principal object of my invention is the provision of switch operating mechanism comprising a flexible connection between an operating member and a switch actuating member wherein the flexible connection serves as a transmission device for normally closing the switch, and which is adapted to collapse in response to an abnormal circuit condition to permit immediate opening of the switch.

A further object is the provision of means for normally restraining the flexible connection in such manner that it is effective to transmit the actuating force to the switch member, and upon occurrence of an abnormal circuit condition permits collapse of said flexible connection at once to allow reverse movement of the switch member to open position.

My invention will be more fully set forth in the following description referring to the accompanying drawings and the features of novelty which characterize my invention will be pointed out with particularity in the claims annexed to and forming a part of this specification.

Referring to the accompanying drawings, Fig. 1 illustrates in diagrammatic form a switch operating and tripping mechanism in position about to effect closure of the switch, Fig. 2 illustrates the mechanism in the position it occupies when the switch is engaged, and Fig. 3 illustrates the mechanism in the position it occupies immediately upon occurrence of the tripping of the switch.

The illustrations, by way of example, may be considered as referring to a solenoid operated circuit breaker, the solenoid (not shown) being connected to the plunger-like operating element 1 pivotally attached at its upper end to one end of a flexible member as a roller chain linkage 2, the other end of which is connected to another plunger-like member 3 comprising a switch actuating

55 The chain or flexible member may be bent through a right angle by a raceway or guide surface 4 so that operation of the solenoid and plunger in a vertical direction is effective to operate the other end of the chain and the plunger 3 in a horizontal direction. The outer side or surface of the chain raceway which restrains the flexible member in 60 its force-transmitting position, and against which the chain presses when the solenoid is moving the switch, or when the switch is closed, consists of a pivotally mounted member 5 which is held in its closed position as 65 illustrated in Figs. 1 and 2 by a latching member as a roller 6 mounted upon the end of a lever 7 pivoted at 8 and controlled in any suitable manner by the usual trip mechanism. A detent or catch 9 which is adapted 70 to enter the slot 10 in the plunger 1 when the latter is in its circuit closing position has pivotally connected thereto a tubular member 11 in which is reciprocally mounted a piston 12 connected by a rod 13 to the 75 plunger 3. A pivot pin 15 mounted on the member 3 coacts with an elongated slot 14 in the rod 13 for a purpose hereinafter described. A spring 16 is interposed between the piston 12 and the closure element 18 at 80 the end of the tubular member 11. When the pin 15 is at the right-hand end of the slot 14, due to the reciprocal movement of the plunger 3, further movement of the latter causes pressure to be applied to the detent 9 85 through the spring 16 and the member 11 so that the detent is caused to enter the slot 10 when the plunger 1 is fully raised, thereby holding the switch mechanism in its closed position. When, however, the switch is 90 tripped to permit opening movement of plunger 3, the recoil of the plunger acting through the rod 13, piston 12, and the lower end of the tubular member 11, forces the detent 9 clear of the slot 10 and into the position 95 illustrated in Fig. 1.

The operation of the mechanism is as follows:

Assuming the parts to be in the position illustrated in Fig. 1, the closing operation of 100

the switch is effected by energizing the solenoid or equivalent motive means to cause upward movement of the operating plunger 1. The movement so imparted to the operating member is transmitted by the flexible thrust-transmitting member or chain 2 to effect an outward horizontal movement of the switch actuating member 3. The latter, through the pin 15, applies pressure in the manner above described to the detent 9 which eventually enters the slot 10 in the plunger 1 and holds it in its switch closing position, as illustrated in Fig. 2. If a fault or abnormal circuit condition occurs, or the switch tripping mechanism is brought into operation, the lever 7 is rotated about its pivot 8 in a counter-clockwise direction and the roller 6 is thereby removed from engagement with the pivoted side member 5 of the raceway. Member 5 under the reactive pressure of the plunger 3 and the chain 2, is forced about its pivot, as illustrated in Fig. 3, and the chain, being no longer restrained in its guide, collapses or buckles to permit reverse movement of plunger 3 to its open circuit position.

The piston 12 during the aforesaid operation engages the lower end of its cylinder or tubular part and forces the detent 9 out of the slot 10 and into its retracted position, as shown in Fig. 1. The operating plunger 1 is now free to fall and the chain returns to the position illustrated in Fig. 1. Upon the resetting of the trip mechanism, the switch can again be operated in the above-described manner, but if a fault or abnormal condition exists, the switch cannot be closed, due to the fact that the member 5 will be freed by the trip lever 7 and will open under the pressure of the chain 2, thereby permitting the same to buckle.

It shall be understood that my invention is not limited to any particular means for operating the switch, as such operation can be effected manually, mechanically or electrically.

It shall be further understood that any suitable means for tripping the switch by releasing the pivoted section of the raceway may be employed, and that the flexible force-transmitting member may operate through other than a right angle without departing from the spirit of my invention.

What I claim as new and desire to secure by Letters Patent of the United States is:—

1. In circuit controlling apparatus including an operating member and a switch actuating member, means interconnecting said members comprising a flexible sliding chain linkage restrained in a force-transmitting position for transmitting motion from the operating member to the switch actuating member to effect circuit closing movement of the last named member.

2. In circuit controlling apparatus includ-

ing an operating member and a switch actuating member, means interconnecting said members comprising a flexible sliding chain linkage, and means for restraining said linkage longitudinally of its movement in a force-transmitting position for imparting motion to the switch actuating member, said last-named means adapted to be removed from restraining engagement with the linkage in response to an abnormal circuit condition to permit opening movement of the switch actuating member. 70

3. In circuit controlling apparatus including an operating member and a switch actuating member, a flexible chain linkage interconnecting said members, means for restraining said linkage within a raceway whereby motion may be transmitted from the operating member to the switch actuating member, and means controlling said restraining means responsive to an abnormal circuit condition whereby release of the restraining means is effective to cause collapse of said linkage and opening movement of the switch actuating member. 80

4. In circuit controlling apparatus, an operating member, a switch actuating member, a flexible thrust-transmitting chain linkage interconnecting said members, means pivotally mounted forming one side of and restraining said linkage within a raceway whereby motion may be transmitted from the operating member to the switch actuating member, and tripping means for releasing the restraining means, thereby causing buckling of said linkage and consequent reverse movement of the switch actuating member. 90

5. In circuit controlling apparatus, an operating member, a switch actuating member, a roller chain interconnecting said members, a lever pivotally mounted for restraining said chain within a raceway in a thrust-transmitting position, and a tripping member for holding said lever in its restraining position, said tripping member being responsive to an abnormal circuit condition for releasing the lever and at once permitting buckling of the chain and opening movement of the switch actuating member. 105

6. In circuit controlling apparatus, an operating member, a switch actuating member, a flexible thrust-transmitting roller chain interconnecting the aforesaid members, a lever forming one side of and restraining said chain within a raceway in a thrust-transmitting position whereby movement of the operating member is effective to transmit movement to the switch actuating member, and tripping means adapted to release said lever from its restraining position, thereby causing buckling of said chain and opening movement of the switch actuating member. 115

7. In circuit controlling apparatus, an operating member, a switch actuating member, a flexible roller chain interconnecting said 120

members, a pivoted lever adapted to form a portion of a raceway for restraining the chain in a thrust-transmitting position, a detent operatively related to the switch actuating member for holding the operating member in its circuit closing position and for releasing it when the switch actuating member moves to its open circuit position, and tripping means adapted to release the free end of said lever thereby permitting the reactive pressure of the switch actuating member to cause buckling of the chain as the switch actuating member moves to its open circuit position.

8. The combination with switch operating mechanism comprising an operating member and a switch actuating member, of thrust-transmitting and releasing means interconnecting said members comprising a roller chain, a pivoted member forming part of a raceway within which the chain is restrained in a thrust-transmitting position, and a tripping member adapted to engage and hold the free end of the pivoted member whereby movement of the operating member is effective to cause corresponding movement of the switch actuating member, said tripping member being responsive to an abnormal circuit condition to release the pivoted member and permit buckling of said chain and consequent reverse movement of the switch actuating member to its open circuit position.

9. Circuit controlling apparatus comprising an operating member, a switch actuating member, a collapsible thrust-transmitting linkage interconnecting said members, tripping means for holding said linkage in thrust-transmitting position, and a locking detent for holding said operating member in the closed circuit position, said locking detent having a resilient connection with said switch actuating member arranged so that said detent is biased into locking position when said switch actuating member is in the closed circuit position and is biased out of locking engagement when said switch member is in the open circuit position.

In witness whereof, I have hereunto set my hand this 13th day of September, 1929.

GEORGE PAILIN.
